MOTOR VEHICLE DOOR VENTILATOR GLASS
MOVING AND INSERTING TOOL

Chester F. Stratton, New Castle, Ind.

Application March 23, 1950, Serial No. 151,408

1 Claim. (Cl. 29—256)

1

This invention relates to tools of the wheel puller type wherein screw actuated clamping elements are slidably mounted in a frame, and in particular this invention relates to a tool having parallel side beams with screw actuated clamping elements slidably mounted in the beams and with a clamp pivotally mounted between the ends of the beams opposite to the ends in which the screw for operating the clamp is positioned.

The purpose of this invention is to provide a tool for readily removing and replacing the triangular shaped glass in similarly shaped frames of motor vehicle door ventilators.

Because of the odd shape of the glass and frames therefor of motor vehicle door ventilators it is difficult to grip the glass when withdrawing the glass from the frame and it is also difficult to hold the glass as it is forced into the frame. With this thought in mind this invention contemplates a tool having side members positioned to be placed over a glass and frame of a motor vehicle door ventilator with a clamp for mounting the side beams on the frame of the ventilator, with clamping elements slidably mounted in the beams for gripping the glass, and with a screw for actuating the glass gripping elements.

The object of this invention is, therefore, to provide means for forming a pulling and pushing tool whereby glass panels may be removed from and inserted in triangular shaped frames without danger of breaking the glass or cutting the hands.

Another object of the invention is to provide a motor vehicle door ventilator glass extractor and inserter that is adjustable to accommodate ventilators of different designs and sizes.

A further object of the invention is to provide a glass extracting and inserting device for motor vehicle door ventilators which is of a simple and economical construction.

With these and other objects and advantages in view the invention embodies a pair of side beams having glass gripping elements of the vacuum cup type positioned between the beams with means for adjusting the tension on the gripping elements, means for actuating the gripping elements, and a clamp for retaining the side beams in position upon the frame as the glass is withdrawn or replaced.

Other features and advantages of the invention will appear from the following description taken in connection with the drawings wherein:

Figure 1 is a side elevational view illustrating the position of the tool on a motor vehicle door ventilator frame.

2

Figure 2 is a plan view of the tool as shown in Figure 1 with the ventilator omitted.

Figure 3 is a longitudinal section through the tool taken on line 3—3 of Figure 2.

5 Figure 4 is a sectional plan through the tool taken on line 4—4 of Figure 1 with the ventilator omitted.

Figure 5 is a cross section through the tool taken on line 5—5 of Figure 1.

10 Figure 6 is a detail showing a section through the clamping element pivotally mounted between the ends of the beams.

Referring now to the drawings wherein like reference characters denote corresponding parts 15 the motor vehicle door ventilator glass extracting and removing tool of this invention is formed with side beams 10 and 11 with split clamping elements 12 and 13 between the beams and positioned at one end of the tool, a screw 14, and with clamping 20 jaws or plates 15 and 16.

In the design shown the beams 10 and 11 are channel shaped in cross section and the screw 14 which is provided with a handle 17 is threaded in a block or bearing 18 secured between the ends 25 of the beams by thumb nuts 19 and 20 on threaded studs 21 and 22, extended from the block 18.

The inner end of the screw 14 is provided with a head 23 that is positioned in a socket or recess 24 in a traveling block 25 that is secured in sockets 26 and 27 in the ends of the jaws 15 and 16, respectively. The socket 26 is formed by extending fingers 28 and 29, as shown in Figure 1 and the socket 27 is formed by extending fingers 30 and 31, as shown in Figure 3.

35 The inner faces of the gripping jaws 15 and 16 are provided with lining strips 32 and 33, respectively which are formed of rubber or other suitable resilient material and the inner faces of the strips or liners 32 and 33 are provided with recesses 34 and 35 that form vacuum cups to facilitate gripping the side surfaces of a glass panel 36 of a ventilator frame 37, as shown in Figure 1.

40 Thumb screws 38 and 39 are provided in the sides of the beams for urging the gripping jaws against the side surfaces of the glass to facilitate gripping the glass, particularly when removing the glass from the frame. The screw 38 is threaded through a lug 40 in the side of the beam and the screw 39 is threaded through a similar lug 41 in the beam 11.

45 The tool is mounted on the frame of the ventilator by a clamp including the gripping jaws 12 and 13 which are pivotally mounted on a bolt 42 in the ends of the beams and the bolt is provided 55 with a thumb nut 43. The gripping elements 12

and 13 are carried on the ends of bars 44 and 45 and studs 46 and 47 extend from the bar 45 through openings in the bar 44, in which they are held by thumb nuts 48 and 49.

The traveling block 25 is provided with lugs 50 and 51 that are slidably mounted in slots 52 and 53, respectively, in the webs of the beams 10 and 11 and the lugs are secured in position by screws 54 and 55 with washers 56 and 57 under the heads thereof.

The screws are threaded into the lugs 50 and 51 respectively.

With the parts arranged in this manner a ventilator from which it is desired to remove the glass panel is positioned between the beams 10 and 11 with the frame of the ventilator secured between the jaws 12 and 13 and with the glass panel gripped between the jaws 15 and 16. With the jaws 15 and 16 securely clamped against the surfaces of the glass panel by the screws 38 and 39 the screw 14 is rotated in a counterclockwise direction whereby the gripping jaws 15 and 16 withdraw the glass panel from the frame. A new panel is inserted in the frame in the same manner with the screw 14 rotated in a clockwise direction.

It will be understood that modifications may be made in the design and arrangement of the parts without departing from the spirit of the invention.

What is claimed is:

A tool for removing and inserting a ventilator glass, comprising a pair of side beams of channel shaped cross section, a bearing secured between

the ends of said beams, a screw member arranged in threaded engagement with said bearing, a handle mounted on the outer end of said screw member, a head arranged on the inner end of said screw member, a pair of opposed jaws interposed between said pair of beams, fingers extending from said jaws and defining sockets, a movable block secured in said sockets and provided with a recess for receiving the head on said screw member, said beams being provided with inner slots, lugs on said block slidably engaging said slots, lining strips of resilient material positioned on the inner surfaces of said jaws and provided with a plurality of recesses providing vacuum cups for engagement with the side surfaces of the ventilator glass, thumb screws extending through said beams for urging said gripping jaws against the side surfaces of the ventilator glass, a clamp including a pair of opposed bars positioned between said beams at the opposite end from the bearing, and gripping jaws on the inner ends of said bars.
